(57) **CLAIM**

The ornamental design for a television receiver, as shown and described.

DESCRIPTION

1. Television receiver

1.1 is a front perspective view of a television receiver showing the new design;

1.2 is a front view thereof;

1.3 is a rear view thereof;

1.4 is a left side view thereof, the right side being a mirror image thereof;

1.5 is a top view thereof;

(Continued)

- 1.6 is a bottom view thereof;
- 1.7 is a rear perspective view thereof;
- 1.8 is a rear perspective view of the television receiver in an alternate configuration, showing the upper cover opened backward and the hidden display from within the main body;
- 1.9 is a front perspective view of the television receiver in an alternate configuration;
- 1.10 is a front view thereof;
- 1.11 is a rear view thereof;
- 1.12 is a left side view thereof, the right side being a mirror image thereof;
- 1.13 is a top view thereof;
